DESIGN FOR A COMBINED ELECTRIC CIGAR LIGHTER AND SUPPORT

Thomas O. Wright, Atlanta, Ga.

Application June 30, 1936, Serial No. 63,587

Term of patent 14 years

To all whom it may concern:

Be it known that I, Thomas O. Wright, a citizen of the United States, residing at Atlanta, in the county of Fulton and State of Georgia, have invented a new, original, and ornamental Design for a Combined Electric Cigar Lighter and Support, of which the following is a specification, reference being had to the accompanying drawing, forming part thereof.

Figure 1 is a perspective view of a combined electric cigar lighter and support showing my new design; and

I claim:—

The ornamental design for a combined electric cigar lighter and support, as shown.

THOMAS O. WRIGHT.
